Des. 211,608
Patented July 2, 1968

211,608

BUTTON-MAKING MACHINE

Lynn Pressman Gray, 115 Central Park W.,
New York, N.Y. 10023

Filed Apr. 28, 1967, Ser. No. 6,877

Term of patent 14 years

(Cl. D55—1)

FIGURE 1 is a view in perspective of a button making machine showing my new design;

FIGURE 2 is a top plan view thereof;

FIGURE 3 is a rear elevational view thereof;

FIGURE 4 is a front elevational view thereof; and

FIGURE 5 is a side elevational view thereof.

I claim:

The ornamental design for a button-making machine, substantially as shown.
